BRACELET

Samuel A. Bastio, Canonsburg, Pa.

Application February 8, 1951, Serial No. 14,134

Term of patent 7 years

(Cl. D45—4)

To all whom it may concern:

Be it known that I, Samuel A. Bastio, a citizen of the United States, residing at Canonsburg, in the county of Washington, and State of Pennsylvania, have invented a new, original, and ornamental Design for a Bracelet, of which the following is a specification, reference being had to the accompanying drawing, forming part thereof.

Figure 1 is a top plan view of a bracelet showing my new design;

Figure 2 is an edge elevational view;

Figure 3 is a side elevational view thereof; and

Figure 4 is also a side elevational view of the same as it appears when seen from the side opposite the side shown in Figure 3.

I claim:

The ornamental design for a bracelet as shown.

SAMUEL A. BASTIO.
